COMPOSITION FOR TREATMENT OF
SEEDSJoseph Roy Booer, Addiscombe-Surrey, England,
and Gustav Kossel, Hackensack, N. J.No Drawing. Application January 17, 1936,
Serial No. 59,550

6 Claims. (Cl. 167—38)

This invention relates to seed disinfectants, more particularly to the eradication or control of fungus diseases of seeds.

The use of organic mercury compounds for the control of such diseases has been practiced for some years more or less successfully. Many such compounds have been described in the literature, and they have been used in the form of solutions and emulsions, and mixed with solid inert diluents in the form of dusts. However, many of these prior art compounds did not prove successful for the control of the disease or resulted in injury to the seeds. Other compounds which gave good results in disease control, had certain collateral disadvantages.

It has recently been demonstrated (Dillon Weston & Booer—Journal of Agricultural Science, Vol. XXV Part IV, Oct. 1935) that highly efficient organic mercury compounds for this purpose are those of the type $R-Hg-X$ in which R is an unsubstituted hydrocarbon radical and X is an acid radical. These compounds are in principle the salts produced by the neutralization of the alkali $R-Hg-OH$ with an acid. While these compounds gave excellent results in seed disease control, being highly effective in small amounts, they possessed the disadvantage that they have a disagreeable odor in some cases, are somewhat toxic and in certain circumstances have a vesicant action.

The present invention is intended and adapted to overcome the disadvantages of the prior known compounds, it being among the objects thereof to provide a method of and a composition for the treatment of seeds, which will be highly effective, relatively non-toxic, non-odorous, and non-vesicant.

It has now been found and the present invention is based on this discovery, that certain members of the group of organic mercury compounds designated by the general formula $R-Hg-NH-R'$ where R is an unsubstituted hydrocarbon radical such as methyl, ethyl, phenyl, and tolyl, and the group $NH-R'$ is the radical of any organic nitrogen compound in which one or more hydrogen atoms are directly attached to a nitrogen atom, retain the strong fungicidal properties of the group $R-Hg$, and can be used for the control of seed borne fungus diseases by applying them to seeds in appropriate quantities either in solutions, emulsions, or as dry dusts after intimate incorporation with an inert diluent. R' is a carbon containing radical in which the carbon is directly attached to the nitrogen and said radical may contain nitrogen and oxy-

gen as well as hydrogen, such as $-CN$ and $-CONH_2$. The toxic and other objectionable properties of the preparations containing the previously proposed organic compounds of mercury in the form in which they are normally applied to seeds are substantially reduced by virtue of the use according to the invention as the active principle of mercury compounds of the type $R-Hg-NH-R'$.

Compounds of the type $R-Hg-NH-R'$ are to be distinguished from compounds of the type $R-Hg-X$ where X is an acidic radical, in that the former are derived from organic nitrogen compounds of the type H_2N-R' which are not acids, and therefore the compounds $R-Hg-NH-R'$ are not salts.

Among the type compounds included in the present invention are those of the type

$R-Hg-N=R'$

where R' is a divalent radical which is that of the di-aryl and di-alkyl substituted guanidines.

The amount of mercury compound in the composition may vary within wide limits and is dependent on a number of factors, such as the character of the seeds, the type of disease to be controlled, the nature of the diluent, the particle size, and the like. In general, it may be said that the amount of mercury compound varies from 0.1% to 3.0% of the diluent or filler used. The amount of composition used on the seeds also varies with a number of factors, but usually from 1 to 8 ounces are used per bushel of seeds.

The following examples will serve to illustrate the invention:

Example 1

To a saturated solution of urea is added slowly and with constant stirring at ordinary room temperature a concentrated solution of ethyl mercury hydroxide. A reaction occurs resulting in the precipitation of crystals of a compound having the formula $C_2H_5HgNHCONH_2$. The precipitate is filtered, dried, and then mixed with 100 times its weight of clay and the mixture ground for a sufficient length of time to uniformly distribute the mercury compound on the diluent.

Example 2

A solution of calcium cyanamide is added to a suitable amount of precipitated calcium sulphate and thoroughly mixed therewith. To the mixture is then added with stirring a solution of methyl mercury sulphate at ordinary room temperature. A reaction occurs resulting in the for-

mation of the mercury compound in situ according to the following equation:

5 The mixture of inert diluent and mercury compound is dried in a rotary drier and ground to a suitable degree of fineness.

10 The above cited examples are for the purpose of illustrating the invention and are not to be construed as limiting the same. Various modifications may be made within the spirit of the invention. For example, other diluents may be used in place of those mentioned above. Other nitrogen compounds may be used in place of 15 urea and cyanamide, as the aryl and alkyl substituted guanidines, aryl and alkyl amines, thioureas, substituted ureas, and the like. While certain proportions of mercury compound in the composition have been specifically set forth, the 20 invention is not limited thereto and the proportion of mercury compound may vary within considerably wide limits. Less than 0.1% or more than 3.0%, even up to 6.0% or 8.0% of mercury compound may be used in the composition, depending upon the circumstances and the character of the application. These and other changes may be made in the present invention, the scope of which is set forth in the claims appended hereto.

25 30 What we claim is:

1. A composition for controlling fungus diseases of seeds comprising a mercury compound having the general formula

35 $\text{R}-\text{Hg}-\text{NH}-\text{R}'$

wherein R is an unsubstituted aliphatic hydrocarbon radical and R' is a radical consisting of carbon and nitrogen atoms and in which carbon is directly attached to nitrogen.

2. A composition for controlling fungus diseases of seeds comprising an alkyl mercury nitrogen compound having the formula

3. A composition for controlling fungus diseases of seeds comprising an alkyl mercury nitrogen compound having the formula

4. A composition for controlling fungus diseases of seeds comprising an alkyl mercury nitrogen compound, the mercury being linked to both the alkyl and nitrogen radicals, having a hydrogen directly attached to said nitrogen, and having a group containing only carbon and nitrogen directly attached to said nitrogen.

5. A composition for controlling fungus diseases of seeds comprising an alkyl mercury nitrogen compound having the formula

25

6. A composition for controlling fungus diseases of seeds comprising a mercury compound taken from the class consisting of RHgNHCONH_2 , RHgNHCSNH_2 , RHgNHCN , RHgNH aryl, RHgNH alkyl, $\text{RHgNC}(\text{NH aryl})_2$, $\text{RHgNC}(\text{NH alkyl})_2$, wherein R is an unsubstituted aliphatic hydrocarbon radical.
